ABSTRACT OF THE DISCLOSURE

Gasoline boiling range aromatics are recovered from a sulfolane extract containing sulfolane, gasoline boiling range aromatics, and minor amounts of light paraffins by extractive stripping in the presence of added heavy paraffinic hydrocarbon to remove the light paraffins and fractionation to separate the aromatics and sulfolane.

BACKGROUND OF THE INVENTION

This invention relates to an improved process for separating and recovering aromatics from mixtures of gasoline boiling range hydrocarbons by extraction with sulfolane. More particularly it relates to the recovery of aromatics from a sulfolane extract.

It is well known that when mixtures of aromatic and non-aromatic hydrocarbons are contacted with sulfolane the aromatic hydrocarbons preferentially dissolve in the sulfolane. Liquid/liquid extraction processes employing this principle have been developed for isolation of aromatics. In these processes it is possible to select extraction conditions to effect a very efficient removal of aromatics into the sulfolane extracting liquid. Unfortunately, at such conditions sulfolane also dissolves minor but significant amounts of light paraffins. When the aromatics are later recovered from the sulfolane extract, for example by distillation, they contain these light paraffins which are deleterious to the aromatic quality.

One solution to this problem is to remove these light paraffins from the sulfolane extract by taking them overhead in an extractive stripper before recovery of the aromatics from the extract. However, foaming problems are often encountered in such extractive stripping. This foaming seriously limits stripper efficiency. Addition of conventional anti-foam agents such as silicones, alcohols, and the like is unattractive as large amounts of these relatively expensive materials must be used, and they may also contaminate the recovered hydrocarbon products.

STATEMENT OF THE INVENTION

It has now been found that aromatics can be recovered with improved efficiency from a sulfolane extract which contains sulfolane, aromatics and minor amounts of closely boiling light paraffins by first extractively stripping the extract in the presence of minor amounts of added heavy paraffinic hydrocarbons to remove residual light paraffins and then fractionating the resulting stripped extract to remove the aromatics as a distillate fraction and to isolate the sulfolane and added heavy paraffinic hydrocarbons as a second bottoms. Very small amounts, generally not more than 100 p.p.m. by weight, of heavy paraffinic hydrocarbons need be added. When sulfolane-containing fractionation bottoms are not recycled, there is no product contamination problem. If the bottoms are recycled, small amounts of the heavy paraffin may appear in the non-aromatic raffinate, but if desired it can be removed by distillation. For this reason its initial boiling point is desirably at least about 15° C. higher than the end

2

boiling point of the non-aromatics in the mixture. This invention is very suitably employed in processes for the separation of aromatics from mixtures of gasoline boiling range hydrocarbons.

5 In the following description of the invention reference will be made to the accompanying drawing wherein the single figure represents, more or less diagrammatically, one form of apparatus suitable for carrying out the invention.

DETAILED DESCRIPTION OF THE INVENTION

The improved recovery process of the invention may be generally employed in the separation of aromatic hydrocarbons from non-aromatic hydrocarbons, for example, naphthenic or aliphatic hydrocarbons. Preferably it is employed in the separation of gasoline boiling range aromatics from similar-boiling non-aromatics, that is, the separation of aromatics of from 6 to about 9 carbons from paraffins of from about 5 to about 9 carbons and naphthenes of from about 6 to about 9 carbons. Suitable feedstocks also include narrower boiling hydrocarbon mixtures, such as, for example, mixtures of benzene, cyclohexane, heptanes, mixtures of toluene, methylcyclohexane, and octanes, or mixtures of xylenes, ethylbenzene, dimethylcyclohexane, ethylcyclohexane, and nonanes.

20 The paraffinic hydrocarbon which is added to the extractive stripper feed is liquid and preferably has an initial boiling point that is from about 20° C. to about 75° C. higher than the end boiling point of the non-aromatics in the hydrocarbon feed mixture. Most preferably, the added liquid heavy hydrocarbon has an initial boiling point that is from about 30° C. to about 75° C. higher than the end boiling point of the non-aromatics in the hydrocarbon feed mixture. Branched- and straight-chain paraffins may be used.

25 In the separation of gasoline boiling range materials, paraffins of from about 11 to 20 carbon atoms are very suitable as added heavy hydrocarbons.

30 A very suitable source of heavy paraffins for use with gasoline boiling range hydrocarbons is an essentially aromatics-free paraffin kerosene or a gas oil boiling range mixture of paraffins.

35 Only minor amounts of heavy paraffinic hydrocarbon need be added to the stripper to obtain the benefit of the invention. Additions of from about 0.001 p.p.m. by weight to about 100 p.p.m. by weight, based on the feed to the stripper, are suitable with amounts of from about 0.002 p.p.m. by weight to about 20 p.p.m. by weight being very suitable and amounts of from about 0.005 p.p.m. by weight to about 10 p.p.m. by weight being preferred.

40 Referring now to the figure, an exemplary application of the invention is as follows. A mixed hydrocarbon stream, containing about 60% by weight of aromatic hydrocarbons of from about 6 to about 8 carbons and about 40% by weight of paraffinic hydrocarbons of 6 to 9 carbons and naphthenic hydrocarbons from 6 to 9 carbons is introduced continuously into the bottom of the liquid/liquid extractor 11, herein shown as a rotating disc contactor, 45 through line 12. Sulfolane (tetramethylene sulfone) is introduced into the top of extractor 11 through line 14. The two liquid streams are contacted in countercurrent. A raffinate low in aromatics is removed through line 15 to phase separator 16 where the raffinate phase is separated from a small sulfolane extract phase. The raffinate phase is removed through line 17. A sulfolane extract stream is removed from extractor 11 through line 19 to phase separator 20 where a sulfolane extract phase is separated and removed through line 21. A small hydrocarbon phase is removed from phase separator 20 and either discarded through line 22 or returned to line 12 through line 24. The sulfolane extract phase from separator 16 passes

through line 25 to line 21. About three p.p.m. by weight of heavy liquid paraffin (e.g., tetradecane) is added to the sulfolane extract through line 26 prior to introducing the extract into extractive stripper 27. Sulfolane extractant is introduced into stripper 27 through line 29. With a minimum of foaming, light paraffins, primarily C_6 paraffins, are separated as an overhead and removed through line 30. A light paraffin-free sulfolane extract is removed through line 31 to fractionator 32 where aromatics are separated as an overhead distillate from sulfolane. The aromatics are removed through line 34 and the sulfolane and added heavy paraffin are removed through line 35 and discarded or preferably at least in part recycled to line 14 and/or 29 through lines 36 or 37 respectively.

The following experiments illustrate the ability of heavy hydrocarbons to reduce foaming during separation of hydrocarbons from a sulfolane-aromatic extract.

(I) A platformate gasoline was extracted with sulfolane to produce an extract containing about 83% by weight sulfolane and about 17% by weight hydrocarbon which was made up primarily of aromatics with 6 to 9 carbon atoms but also contained about 5% paraffins with 5 to 9 carbon atoms and naphthenes with 6 to 9 carbon atoms. This extract was distilled in a glass sieve tray distillation column having an internal diameter of 50 mm. The height of the liquid/vapor foam bed on the glass trays was measured to determine the foaming tendency of the extract. The height of the vapor liquid foam bed on the glass trays was remeasured following the addition of 0.1 p.p.m. of heavy paraffin (hexadecane) and again following addition of 3 p.p.m. by weight of hexadecane. These additions reduced the foam height by 15% and 40% respectively.

(II) Experiment I was repeated, but the heavy paraffin this time was an odorless (paraffinic) kerosene, which was mainly paraffins of 12 to 17 carbon atoms. At a kerosene concentration of 0.01 p.p.m. by weight the reduction in foam bed height was 25%, at a concentration of 3 p.p.m. by weight the reduction was 40%.

We claim as our invention:

1. In the separation of aromatics from a mixture of gasoline boiling range hydrocarbons consisting essentially of paraffins of from 5 to about 9 carbons, naphthenes of from 6 to 9 carbons and aromatics of from 6 to 9 carbons by selective liquid-liquid extraction with sulfolane to form an extract phase consisting essentially of sulfolane, 6 to 9 carbon aromatic hydrocarbons and a minor

amount of light paraffins, the improvement comprising recovering the aromatics in a high state of purity from the residual light paraffin-containing sulfolane extract by (a) subjecting the sulfolane extract to extractive stripping in the presence of from about 0.001 p.p.m. by weight to about 100 p.p.m. by weight of added 11 to 20 carbon liquid paraffinic hydrocarbon to obtain a stripper overhead consisting essentially of residual light paraffins and a stripper liquid bottoms comprising sulfolane, aromatics, and added paraffinic hydrocarbon, and (b) fractionally distilling the stripper liquid bottoms to obtain a distillate consisting essentially of aromatics and a second liquid bottoms consisting essentially of sulfolane and added paraffinic hydrocarbon.

15 2. The process in accordance with claim 1 wherein the added paraffinic hydrocarbon is added in amount of from about 0.002 p.p.m. by weight to about 20 p.p.m. by weight.

20 3. The process in accordance with claim 2 wherein the mixture of gasoline boiling range hydrocarbons to be separated consists essentially of benzene, cyclohexane, and heptanes.

25 4. The process in accordance with claim 2 wherein the mixture of gasoline boiling range hydrocarbons to be separated consists essentially of toluene, methylcyclohexane, and octanes.

30 5. The process in accordance with claim 2 wherein the mixture of gasoline boiling range hydrocarbons to be separated consists essentially of xylenes, ethyl benzene, dimethylcyclohexane, ethyl cyclohexane, and nonanes.
